[57] ABSTRACT

A reciprocating platen unit for bidirectional printing having an arcuate work surface with supports extending radially downward therefrom, mounted in a frame by rollers on the bases of the supports reciprocating in horizontal guideways in the frame and cam follower rollers near the outer ends of the work surface interacting with symmetrical curvilinear cam plates forming upper portions of the sides of the frame. The length of travel of the support rollers and cam follower rollers is slightly more than required to rock the platen fully, thus permitting the platen to drop enough at each end of its excursion for work-piece manipulation. A rod secured between the supports and beneath the platen surface riding in a channeled member pivoted to the frame and an over-center spring provide stabilization of the platen.

FIG. 1.

FIG. 2.

FIG.3.

FIG.4.

1 TOGGLE PLATEN UNIT

BACKGROUND OF THE INVENTION

This invention relates generally to a platen assembly for a printing press and more specifically to an assembly with a platen having an arcuate work surface for printing in a line-by-line fashion with a true rolling motion in each direction of travel.

It is well-known in the prior art to employ a curved work surface platen in a printing press. However, prior to this invention, a platen assembly would usually have to complete an entire two-stroke cycle, returning the platen to its original position, before the curved work surface would be engaged in the printing operation again. Bulky, complex assemblies were often required to accomplish even this cycling of a curved work surface platen which may include elongated tracks positioned outside the range of travel of the platen. Often, sophisticated synchronization was required for coordination of bed band platen operation.

Besides the lack of speed typically associated with a prior art curved work surface platen assembly, there was the tendency for the platen to slide, shift, or wobble during the printing operation due to the pressure between the platen and the bed. Any such sliding, shifting, or wobbling resulted in blurred printed matter, which was further exacerbated by the two-stroke action of the press.

SUMMARY OF THE INVENTION

The principal object of this invention is to improve reciprocating platen units having arcuate work surfaces for line-by-line printing.

Another object of the invention is to develop an improved reciprocating plate unit for high precision printing on each excursion of the platen.

A further object of the invention is to improve the stabilization of reciprocating platens having arcuate work surfaces.

BRIEF DESCRIPTION OF THE INVENTION

In achieving the above-mentioned objects an assembly is provided for reciprocating an arcuate platen wherein lower ends of radially extending supports at each side of the platen are constrained to reciprocal horizontal motion while the motion of the operating end of the platen is restricted by a pair of symmetrical curvilinear-shaped cam plates. The linear horizontal motion of the lower end of the supports is permitted beyond what would be necessary for completion of a printing stroke in order to lower the level of the platen at each end of the excursion for insertion or removal of print media. A rod secured between the supports, riding in a pivoted channeled member, and an over-center spring stabilize the platen.

BRIEF DESCRIPTION OF THE DRAWINGS

The foregoing objects and advantages of the invention, together with other objects and advantages, which may be attained by its use, will be apparent from the following detailed description when read in conjunction with the drawing, wherein like numerals identify corresponding elements:

FIG. 1 is an isometric perspective view of a toggle platen illustrating the orientation of various elements of the present invention;

2

FIG. 2 is a cross section of the toggle platen taken along line 2-2 of FIG. 4;

FIG. 3 shows the view of FIG. 1 partially broken away;

FIG. 4 is a front elevation view of the toggle platen of FIG. 1 with a flat bed disposed thereabove.

DESCRIPTION OF THE PREFERRED EMBODIMENT

10 The toggle platen of the invention is preferably incorporated in a flat bed printing press in which a stationary bed 12 (FIG. 4) is horizontal and above the platen. The platen assembly is preferably firmly mounted on a base 11 (FIG. 1) but, of course may be affixed directly to a floor or other foundation.

A frame 13 defined by parallel and opposite outer sidewalls 14 extends upwardly from the base 11 for providing the principal support and restraints for the arcuate work surface platen 23. The platen 23 is integrally attached to supports 25 extending radially downwardly and inwardly from each end of the lower, or concave, surface of the platen. The supports 25 are attached at the center of the arc of the arcuate surface of the platen 23. Mounted on the lower end of each of the supports 25 is a roller 29 which is constrained to linear and preferably horizontal movement by a guideway 17 in the form of a slot cut out of each of the sidewalls 14 of frame 13. A restraint abutment 19 may be inserted at each end of each slot 17 for protection of the rollers 29. The abutment 19 may be formed of such well-known materials as gum rubber, or a rubber plastic composition, for example.

The radius of curvature of the work surface 27 is substantially equal to the perpendicular distance between the parallel paths of the axis of the horizontally constrained support rollers 29 and the advancing print line across the bed 12 of the printer. Therefore, any desired radius of curvature of the work surface 27 may be employed if the bed 12 is positioned the corresponding distance above the axis of the support roller. Whenever the toggle platen 23 is engaged in printing, the line of contact between the arcuate work surface 27 and the bed 12 will be directly above the support rollers 29.

45 With any given radius of curvature of the work surface 27, the operative segment of the arc will usually be designed according to the maximum length of printing on a page. For example, if the maximum length of printing on a page is 12 inches then the operative arc 50 of the arcuate work surface 27 must be at least 12 inches and the radius of curvature will dictate the length of the platen segment.

Cam follower rollers 33, 35 are rotatably mounted on the outer surfaces of supports 25 near each end of the platen segment and proximate the side edge of the curved work surface 27. Curvilinear cams 21, preferably symmetrical about axis 22 (FIG. 1) are formed on the edges of the sidewalls 14 of the frame 13 and restrict the cam follower rollers 33, 35 such that the curved work surface 27 rolls, without sliding, in a straight line motion in each direction.

The exact contour of the curvilinear cams 21 is purely a function of where the cam follower rollers 33, 35 are positioned on the supports 25 for any given radius of curvature of the work surface 27. The cam follower rollers 33, 35 are preferably secured to supports 25 equidistant from the center of the arc of the work

surface 27 thereby defining the curvilinear cam surfaces 21 as symmetrical.

A brace rod 37 (FIGS. 2 & 4) joins the supports 25 under the lower or concave surface of the platen 23 at the center of the arc for added platen strength and integrity by keeping the supports 25 from spreading outwardly under the platen pressure as it cooperates with the bed 12.

Hooks 45 (FIGS. 3 & 4) are journaled on each end of the brace rod 37 just inside each of the supports 25. The top ends of over-center springs 43 are attached to hooks 45 while the bottom ends of the springs 43 are secured to either the base plate 11, a foundation, or hooks 47 journaled to the bottom of frame 13 and extending upwardly therefrom adjacent the center of the horizontal guideways 17.

The major portion of the length of brace rod 37 is spanned by a stabilizer channel member 39 having integral flanges 40 extending downwardly from each end. At a point opposite each axis of symmetry 22 of the curvilinear cam plates 21 the flanges 40 are pivotally secured to an inner frame comprising support plates 15 disposed inside the supports 25. The inner support plates 15 are firmly attached to the base 11 or other foundation.

Opposite parallel inner walls 42 of the stabilizer channel 39 (FIG. 2) maintain sliding contact with the brace rod 37 and provide the channel member 39 with sufficient depth to continuously constrain the brace rod 37 while it rides up and down therein as the platen 23 is reciprocated. With the brace rod 37 thus constrained to ride within the stabilizer channel 39, the platen 23 is prevented from lateral twisting with respect to the guideways 17 and the camming surfaces 21 or otherwise wobbling in the frame 13.

Any standard drive train may be connected to either or both of the supports 25, or to the axles 30 of the rollers 29 for imparting reciprocating movement to the supports 25 and thereby to the platen 23.

The reciprocating platen 23 prints in a true line-by-line fashion via the curved work surface 27 as the rollers 29 are reciprocated between the abutments 19 of the linear guideways 17. The rollers 29 are driven along the guideways 17 during the first part of each excursion against the bias of the overcenter springs 43 (FIG. 3 & 4). After the platen 23 has passed the center of its excursion the springs 43 add their accumulated energy to the drive on the supports 25 to bring the platen quickly to the end of the printing operation. The over-center springs 43 enable the platen 23 to be toggled between stable states at each end of the excursion of the platen. The springs 43 cooperate with the channel member 39 to stabilize the platen for preventing undesired slide, shift, or wobble of the arcuate work surface during the true line-by-line high precision bidirectional printing operation.

Whenever the support rollers 29 are at rest against abutments 19 at either end of the guideways 17, the reciprocating platen 23 is in a stable state. The platen is oscillated between these stable states by actuating whatever drive means is coupled to the toggle unit. For instance, when force is applied to a handle 41 coupled to a support 25 (FIG. 1) the platen supports 25 are driven along the horizontal guideways 17. While the support rollers 29 are thus moving from one end to the other of the horizontal guideways 17, cam follower rollers 33, 35 are moving in opposite directions along the

peripheries of the symmetrical curvilinear cam portions 21 of the sidewalls 14 of frame 13.

For example, if the support rollers 29 are against the right abutments 19, as seen in FIGS. 1 and 3, then the right cam follower rollers 35 engage the top of the right side of symmetrical curvilinear cam portions 21 of the sidewalls 14, while the left cam follower rollers 33 engage the bottom ends of the left side of the curvilinear cam portions 21 of the sidewalls 14. As the support rollers 29 roll along the guideway 17 toward the left abutments 19, the right cam follower rollers 35 moves downward along the periphery of the right side of the cams 21. Being so restricted, the arcuate work surface 27 of the platen 23 will rock from right to left. This movement of the work surface 27 produces true line-by-line printing from right to left when employed in conjunction with a stationary flat bed 12 or with an identical toggle platen unit in synchronization and facing relationship substituting for a flat bed 12.

The length of the guideways 17 and the length of the cam portions 21 being extended beyond that which is necessary for completion of a printing stroke, permits the platen 23 to drop slightly at the end of printing resulting in a lowering of the entire arcuate work surface 27.

By so lowering the platen 23 clearance is provided so that a print medium (not shown) may be passed between the arcuate work surface 27 and the stationary bed 12 without further movement of either the stationary bed 12 or the platen 23.

Another means for permitting print medium manipulation other than the above-disclosed extension of curvilinear cam plates 21 and horizontal guideways 17 is by providing cut-out or shallow open areas portions 50 (FIGS. 1 and 3) extending into both ends of the arcuate work surface 27 extending into work surface otherwise available for printing. Of course, the cut-out portions 50 would have to be slightly wider than the width of the print medium, and therefore span almost the entire width of the work surface and also slightly deeper than the thickness of the print medium.

Another alternative for providing print medium clearance is to combine the cut-out means and extension means such that the cut-out portion 50 would extend into the printing area of the work surface 27 less than the thickness of the print medium, and the curvilinear cam plates 21 and horizontal guideway 17 would not be extended as far as is necessary for dropping the entire platen 23 a distance equal to the print medium thickness. Any combination of cut-out portion 50 depth and cam plate 21 and horizontal guideway 17 extension providing sufficient clearance for print medium manipulation could be employed.

After the print medium has been moved a predetermined length presenting a fresh print medium above the work surface 27 the above operation is reversed beginning with the support roller 29 being moved from its now stable state against the left abutment 19. Now the arcuate surface 27 rises slightly according to the extended contour of the cam 21 and then travels back to the right with a true line-by-line high precision printing operation being completed on a fresh print medium on each half-cycle of oscillation. Therefore, two distinct areas of printing are made for each cycle of oscillation of the platen 23, and the printing rate has been significantly increased.

Although the prime embodiment of the invention was described in a printing press environment, it is obvious

that the invention would also be useful in almost any environment where an arcuate platen is employed. The curved work surface and the bed could be equipped with various tools (not shown) other than type elements. For example, punches could be mounted on the curved work surface 27 and dies mounted on the bed 12 for punching feed holes along continuous form edges. Likewise a single punch and die (not shown) could be employed for punching envelope windows. It is quite apparent that the invention would be similarly useful in other environments such as pressing, perforating, cutting, transferring, or laminating, wherein arcuate platens operate in combination or singly with a flat surface.

What is claimed is:

1. In a platen assembly having an arcuate work surface and supports extending radially outward from each side of the arcuate work surface of the platen, and a frame for mounting the platen, the improvement comprising:

means for constraining the outward ends of said supports to linear movement;

symmetrical curvilinear cam surfaces on said frame;

cam followers mounted on said platen continuously engaging said curvilinear cam surfaces; and said cam followers cooperating with said constraining means for restricting said arcuate work surface to rolling motion.

2. In the assembly of claim 1 the improvement wherein said constraining means comprises linear guideways in said frame and rollers mounted on the outward ends of said supports for movement within said guideways.

3. In the assembly of claim 2 the improvement further comprising means for enabling said cam followers and said rollers to lower said platen for accommodating workpiece insertion and removal.

4. In a platen assembly having an arcuate work surface for line-by-line printing and including supports extending radially outward from each side of the arcuate surface of the platen, and a frame for mounting said platen, the improvement comprising: means for constraining the outward ends of said supports to linear movement;

symmetrical curvilinear cam surfaces on said frame;

cam followers mounted on the sides of said platen continuously engaging said symmetrical curvilinear cam surfaces; and said cam followers cooperating with said constraining means for restricting said arcuate work surface to rolling motion for bidirectional line-by-line printing.

5. The assembly of claim 4 wherein said improvement further includes bracing means secured between said supports and channelled means slidably enclosing said bracing means for maintaining the line of motion of said platen orthogonal to said lines of printing.

6. The assembly of claim 4 further including toggle means interacting with said platen for adding accumulated energy to said platen during a portion of said printing and for maintaining said platen in a stable state at the end of each printing excursion.

7. In the assembly of claim 4 the improvement wherein said constraining means comprises linear guideways in said frame and rollers mounted on the outward ends of said supports and positioned in said guideways.

8. In the assembly of claim 7 the improvement further comprising resilient abutments at each end of said horizontal guideways for protecting said rollers.

9. In the assembly of claim 4 wherein said improvement further includes shallow open areas extending into and spanning almost the entire width of each end of said work surface for print media manipulation.

10. In a platen assembly having an arcuate work surface and supports extending radially outward from each side thereof, the improvement comprising:

means for constraining the outward ends of said supports to substantially linear movement;

a frame including two opposite sidewalls for mounting the platen;

curvilinear cam surfaces disposed on opposite edges of each of said sidewalls, and

cam followers mounted on said platen, said supports being disposed adjacent and parallel to said opposite sidewalls and said cam followers on said platen continuously engaging said curvilinear cam surfaces between said cam followers and cooperating with said constraining means for restricting said arcuate work surface to rolling motion.
